UNITED STATES PATENT OFFICE

ANDREW JOHANSEN, OF BROOKLYN, NEW YORK

SWITCH MECHANISM FOR TESTING TRANSFORMERS

Application filed June 28, 1927. Serial No. 202,015.

This invention relates to a switch mechanism for testing oil cooled transformers on high tension lines. The terminals of such transformers and of the feeder cables therefor are usually contained within an oil filled container called a pothead. When the feeder cable is to be tested, it is necessary to empty the pothead to get at the terminals and disconnect them from the transformer. This is a time consuming as well as a dangerous operation because the operators are compelled to work in close proximity to the terminals.

The object of my invention is to provide a switch mechanism whereby the disconnecting of the transformer from the feeder cable may be done from outside the pothead without necessitating draining the same. Another object of the invention is to arrange the switch mechanism in such a manner that the operation may be performed at a point remote from the pothead and without requiring the workmen to operate directly on or with the transformer or feeder cable terminals. Still another object of the invention is to provide testing apparatus in a more compact and practical manner than heretofore. Other objects of the invention will appear as this specification proceeds.

In some respects this application is a continuation of or further development of the inventions of similar character disclosed in my pending patent applications Serial Number 102,099, filed April 15, 1926, and Serial Number 112,435, filed May 29, 1926.

Accordingly my invention is embodied in a switch mechanism or device arranged and constructed as hereinafter set forth and as illustrated in the accompanying drawings in which

Fig. 1 is a side view of a transformer and pothead embodying the invention with parts broken away and details omitted.

Fig. 2 is a front view of the pothead with the front wall removed and parts in section.

Fig. 3 is a detail view showing some of the parts in a certain operating position.

Figs. 4, 5 and 6 are similar views showing a modification.

Fig. 7 is a sectional side view of the pot head and the improved testing mechanism.

Fig. 8 is a front view thereof.

Fig. 9 is a detail view of the operating means used in connection with Figures 7 and 8.

Throughout all the views in the drawings, the transformer is marked 1 and the pothead 2. The feeder cable is marked 3 and the terminals of the three phases thereof are marked 4, 4, 4. They are suitably connected within the pothead to three insulated terminal supports 5, 5. The transformer terminals 6 pass from the transformer into the pothead through suitable insulating supports 7 which carry switch clips 8, connected to said transformer terminals.

The terminal supports 5 carry conducting bearings 10 in which switch blades 9 are mounted on an operating shaft 12. The latter has nonconducting portions 13 so that the switch blades serve to connect the feeder cable terminals 4 to the transformer terminals 6 in parallel in an obvious manner. I believe it to be broadly new to connect the transformer and feeder cable phases by means of movable switch blades within the pothead. Heretofore said terminals have been connected by rigid connecting bars, or the feeder cable terminals have been connected directly to the transformer terminals.

In the top of the pothead there is mounted three terminal connectors each of which consists of an insulating body 14 enclosing a connecting stem 15 having a switch blade clip 16 at its lower end and a cable or wire socket 17 at its upper end. When not in use the connectors are protected by suitable caps 18.

In the art, testing of the feeder cable is done by emptying the pothead of oil and thereafter disconnecting the feeder cable from the transformer. The testing apparatus and devices are then connected in various manners to the three disconnected and exposed feeder cable terminals. In the present instance the connectors 14 serve as terminal connectors for the feeder cable terminals. To this end means are provided for rotating the switch shaft 12 to open the switches 9 and connect them with the connectors 14. Such means may take any convenient form. In the present instance the

one end of the shaft is extended to the outside, through suitable stuffing boxes, and carries an arm 20 connected by a link 21 to an operating arm 22 pivoted in any suitable manner at 23. 24 is a handle and by means of a pin 25 passing through a hole in the arm 22 and corresponding holes 26 in the support 27, the arm 22 may be placed in two definite positions in an obvious manner.

The parts are shown in their normal position in Figures 1 and 2. When, however, it is desired to test the feeder cable, the latter is disconnected from the transformer by moving the operating arm into position 28, indicated in dotted lines. Consequently the 15 shaft 12 is rotated and the switches 9 are opened and swung over into the position shown in Figure 3, from which it appears that each switch blade engages the connector clip 16. As a result, the connectors 14 now become outside connector terminals for the 20 feeder cable terminals 4. The operating arm 22 is now fixed in testing position by means of the pin 25. To insure that the blades 9 engage the connector clips 16, the blades may 25 have suitable heel stops 29 which limit their movement in an obvious manner.

The feeder cable is now ready for testing in precisely the same manner as heretofore practised. In Figure 2 the elements 30 denote the wires leading from whatever testing apparatus is to be used. The connector caps 18 are opened or removed after which the test wire terminals 30 may be inserted 35 in the sockets 17 for testing purposes. The tests need not be described because no change is made therein nor in the testing apparatus. When the testing is completed, the switch blades 9 are swung back into normal closed position as is obvious.

In the modification illustrated in Figures 4, 5 and 6, the shaft 12 is eliminated and the switch blades 9 are individually pivoted in the conducting bearings 10. In this case 45 therefore there are separate openings and closing means for the switches.

The switches are opened by a non-conducting opening bar 32 in the form of a yoke which is pivoted in the pothead on each side 50 at 33. On the one side the opening bar is extended outside the pothead and carries an arm 34 connected by a link 35 to an opening arm 36, which is held in normal upper opening position by a pin 37 engaging the support 38. When it is desired to open the switches and connect the feeder cable terminals 4 with the connectors 14, the pin 37 is detached and the arm 36 swung down thereby moving the opening bar into the position 55 shown in Figure 6. The switches are stopped in proper position by the heel stops 29. The operator feels in the arm 36 when the switches are fully opened and he thereafter moves the opening bar back into normal inactive position.

After the testing the switches are closed by a non-conducting closing bar 40 also in the form of a yoke pivoted at 41, 41 in the sides of the pothead and operated by an arm 42 connected by a link 43 to an operating arm 44 which rests in normal inactive position on a stop 45. The operator swings arm 44 upward until he feels that the switches have engaged the transformer terminal clips 8. He then drops the arm 44 back into normal position.

The construction shown in Figures 4, 5 and 6 has the advantage of more positive operation in the opening and closing of the switches, and greater care in conducting the operations by two separate operating arms.

In the modification shown in Figures 7, 8 and 9, the invention is still further developed in that the pothead is arranged for testing in combination with a testing box of novel conception. Testing as practised in the art is done with several different sets or pieces of testing devices, such as a grounding board or box, a lamp set or box and so forth. This invention provides a means for mounting the several parts of the testing apparatus on one panel in a box which may be mounted on the pothead direct or remote therefrom. Referring to Figures 7 and 9, the switches 9 are mounted within the pothead in precisely the same manner as described in connection with Figure 1 and the parts are numbered correspondingly. The non-conducting shaft 12 is extended outside the pothead and operated by means of an arm 50, a link 51 and another arm 52 adapted to be moved into three different predetermined positions by means of a pin 53 adapted to engage three holes 54 in a support 55 in an obvious manner.

On the front wall of the pothead and suitably insulated there are mounted three switch terminals 56 in alignment with the three switch blades 9. Only one set is shown as they are alike. On the outside of the pothead there is mounted a testing box 57 the wall of which forms a switch board 58. The three terminals 56 are connected through the panel to the poles 59 of a three-pole double throw switch 60.

The switch 60 is adapted to be connected to the one side with three switch clip terminals 61 connected to removable testing links 62 which are grounded at 63. When thrown to the other side, the switch 60 engages clips 64 connected to three testing lamps 65 connected in parallel to the pole of a single double throw switch 66. The latter is adapted to ground the lamps by engagement with a terminal clip 67, or it may be thrown to the other side to engage a terminal 68 of a live positive wire 69.

When it is desired to test the feeder cable, the switch 60 is closed on terminals 61 and the arm 52 is moved into position 70 in Fig-

ure 9. This movement causes the switches 9 to engage terminals 56, hence the feeder wires 4 are grounded and the operator ascertains whether the feeder is dead or alive. 5 If the feeder is dead, nothing happens. If the feeder is alive the grounding thereof will cause a flash, the circuit breakers at the central switchboard will open, an alarm will be sounded and so forth the same as occurs with 10 the present testing sets. By removing the links, it is also apparent that each phase of the feeder cable may be tested by grounding. Without going further into details about the tests themselves which are no part 15 of this invention it is obvious that when the switches 9 are closed on 56, and grounded through the switch 60 and the links 62 removed, the terminals at 71 become outside terminals of the feeder cable and accessible for 20 testing.

For other tests, the switches 9 remain closed on terminals 56, but the three pole switch is thrown to the lamp side of the panel. If now the single pole switch 66 is thrown to 25 ground at 67 and the operator at the other end of the line sends current through one of the phases, the particular lamp will light up if the phase is correctly connected, otherwise not. Similarly, other tests such as the 30 loop test, phase identifications test, and so forth, are easily and quickly made by means of the testing box 57 and they need not be described.

When the operating arm 52 is moved into 35 position 72, the switches 9 engage the connector clips 16, and high potential tests may be made by inserting the ends of the testing wires in the connectors the same as described above. When the arm 52 is in position 74, the 40 switches 9 again connect the feeder and the transformer.

It will be seen, therefore, that with the construction shown in Figures 7, 8 and 9, a very simple and practical testing device is provided for quickly and conveniently making the several tests. The test box 57 need not be mounted on the pothead but may be located a distance therefrom, or be portable, in which case of course the terminal clips 56 within 45 the pothead will be connected by suitable cables to the switch terminals 59 in an obvious manner and not shown.

From the foregoing it will be apparent that my invention provides means for disconnecting the feeder cable from the transformer without opening the pothead, and that the work of testing may be done without the workmen being compelled to operate directly on the several terminals, then eliminating a 55 very dangerous feature of the work.

The construction and installation of my improved testing apparatus is inexpensive and easily made. Its operation does not require any greater skill than is necessary with 60 the devices heretofore used. It will further

be apparent that the invention lends itself readily to such modifications and changes as may be required for local purposes and without departing from the spirit of the invention or the scope of the appended claims. 70

I claim:

1. In combination, a transformer and feeder cable therefor, a pothead containing oil, insulators for supporting the transformer and feeder cable terminals within the pothead so as to be connected in parallel, a plurality of switch terminals on the inside of the pothead and connected to testing devices outside of the pothead, connectors for testing purposes mounted in the wall of the pothead, 75 switches within the pothead mounted on the feeder cable terminals and means outside the pothead for operating said switches into one of three different positions, viz, connecting the feeder cable terminals to the transformer 80 terminals, or to the said connectors, or to the said switch terminals at will.

2. A switch mechanism of the character described comprising in combination a closed container, a plurality of pairs of terminals within the same, switch blades connecting each pair of terminals, a connector for each pair of terminals extending from outside the container to within the same, a switch opening bar within the container for disconnecting said switch blades from the one terminal in each pair and connect said switch blades to the said connectors, means remote from said container for operating said opening bar, a switch closing bar for disconnecting the switch blades from the connectors and again connect them in each pair of terminals and means remote from the container for operating said switch closing bar. 95
